PROCESS OF TREATING HYDROCARBONS

Application filed May 21, 1929. Serial No. 364,810.

The present invention relates to the cracking of hydrocarbons in the gaseous and/or vapor phase to convert the same principally into aromatic compounds typified by benzene, toluene, and xylene.

It has been proposed to convert propane, butane and the like, partially into crude benzol by cracking both in the presence of and in the absence of catalysts. The prior art workers, in an empirical way, have cracked ethane, propane and butane and mixtures thereof in a heated tube, and obtained light oils, gaseous products and a heavy tar. However, in investigations of this character, the chemical reactions occurring were not thoroughly understood, and insufficient importance was attached to the time factor involved in the conversion of the hydrocarbons. We have made extensive investigations to study in a somewhat exhaustive manner the sequence of changes occurring during the cracking of hydrocarbon gases, and particularly propane and butane into aromatic compounds and oils and tar, and to further determine in a fairly quantitative degree the effect of temperature on the nature of these consecutive changes and on the velocity with which they occur.

Our experiments show that at temperatures of 1250° to 1750° F., and under atmospheric pressure, the cracking of hydrocarbons, typified by propane, butane and mixtures of the same, proceeds endothermically with an increase in volume and the formation of simple gaseous olefines to a maximum of 35 to 50% by volume, by familiar reactions in which the paraffin molecule splits into two molecules, one an olefine, and the other a simple paraffin or hydrogen. We have ascertained definitely that in the case of propane or butane, the heat absorbed by the endothermic reaction reaches a maximum of about 700 B. t. u. per pound at approximately 1562° F., at which state of maximum heat content, the olefine content is approximately at the

maximum. At approximately the temperature specified, this condition is attained in somewhat less than 0.002 minutes. At higher cracking temperatures within the range (1250° to 1750° F.), both olefine content and heat content attain a somewhat higher maximum value than at the lower ones. The time consumed by this stage of reaction decreases rapidly with increase in the temperature at which it occurs.

The higher temperatures of cracking as before stated give a higher content of the olefines than the lower temperature for that time of cracking, characteristic for each temperature, giving the maximum volume percent of olefines. The chief reason for this is that the decomposition of ethane to ethylene and hydrogen $C_2H_6 \rightarrow C_2H_4 + H_2$ - 37900 cal. is reversible and rapid and endothermic at temperatures within our cracking range. The higher the temperature, the more completely is the ethane dissociated at equilibrium. Ethane, ethylene and hydrogen are all formed in the early cracking reactions, and, though influenced of course by other reactions in which ethylene is destroyed, a hydrogenation equilibrium is nevertheless approached. As a result, much of the ethane we find in the gases produced by cracking at a low cracking temperature, appears as ethylene and hydrogen at a high cracking temperature and augment the unsaturates content of the gas, and, since the dissociation is endothermic, the heat content of the gas. The unsaturates attains a maximum 10-15 percent higher at 1562° F. cracking temperature, than at 1112° F.

Our experiments indicate that continued exposure to the cracking temperature causes the olefines produced by the initial cracking to undergo an exothermic conversion or decomposition into aromatic oils and tar after a period of no less than ten times as long as that required to effect the endothermic decomposition or conversion.

In endothermic cracking, it happens that the reaction in the useful temperature range (1250-1750° F.) is so rapid that a practical coefficient of heat transfer through confining surfaces as in a tube coil, develops a temperature at which the reaction will just absorb the heat furnished. Furthermore, in the early stages of endothermic cracking, the velocity of cracking is greater than in the later stages, and a somewhat lower temperature is therefore developed than in the later stages of endothermic cracking. The time of cracking at a single temperature, moreover, is more or less incidental to the economically rapid introduction of the endothermic heat. In our experience, a tube coil operating at full capacity permitted the introduction of all the endothermic heat with an exit temperature in the gas of 1400-1425° F. An exit temperature above 1450° F. showed the instability characteristic of an incipient exothermic reaction. The value of 0.002 minutes at 1562° F., is a maximum value, and an exposure time for exothermic cracking ten times that long, 0.02 minutes, is a minimum value for developing a maximum amount of volatile oils. Unlike the endothermic cracking, this value has been determined fairly accurately by us and is long enough to be significant and indicate that a reaction chamber is desirable, and indicate the size to be used. A value for this ratio as high as 50 is permissible, corresponding to an exothermic cracking time of 0.10 minutes which gives a substantially optimum yield of volatile oils also, but how much greater the maximum value would be, since the time of endothermic cracking given of 0.002 minutes is a maximum value we have not determined. A maximum yield of benzene and toluene is thus developed, accompanied by a somewhat less amount of tar, and very little carbon. During this period, relatively little change occurs in the volume of the gas. However, of course, the olefine content of the gas decreases progressively. The heat evolved during this stage in cracking propane or butane to a maximum yield of simple aromatics, is about 350 B. t. u. per pound, at a cracking temperature of 1562° F., at which temperature a period of 0.04 to 0.08 minutes is required.

We have discovered that the temperature is related to the duration of this exothermic cracking stage by the empirical formula

$$T = 1245 - 180 \log_{10} t$$

in which T =temperature in degrees Fahrenheit and t =time in minutes.

This formula applies for temperatures varying approximately between 1250° to 1550° F. It is somewhat less accurate when utilizing higher temperatures up to 1750° F.

In regard to said formula, it may be stated that experiments were conducted with the ob-

ject of determining the role of cracking time as well as temperature in producing an optimum yield of benzol. A gas of the composition

	Per cent	70
Methane	18.6	
Propane	44.7	
Butane	36.7	
	100.0	75

was submitted to cracking in a non-catalytic silica tube under conditions suitable for the production of benzol. The experiments were conducted at atmospheric pressure and the carbon, tar, benzol and gases were separately measured. The effect of time and temperature on benzol yield is shown in the following table, in which time is expressed in minutes and benzol yield in gallons per thousand cubic feet of gas.

Table.—Effect of time of cracking on benzol yield at several temperatures.

Time	Yield	90
1292° F.		
.5	1.5	
1.1	1.7	
3.5	1.8	
1382° F.		
.28	1.8	
.38	2.1	91
2.6	2.1	
1562° F.		
.012	1.7	
.031	1.9	
.066	1.8	
1742° F.		
.003	2.1	
.006	1.9	92

At a given temperature, the yield of benzol was observed to increase gradually as the cracking time increased, until a virtually maximum yield was developed. A several fold increase in time beyond the minimum necessary to develop a virtually maximum yield caused little change in benzol yield, but tar formation was increased, of necessity through depletion of the gas. The increase in temperature increased the reaction velocity without greatly influencing the sequence of changes taking place during cracking. The maximum yield of benzol was roughly constant throughout the rather wide temperature range studied within the time range appropriate to and unique for each temperature.

The data of the table show the minimum time required to obtain a substantially optimum yield of benzol at several temperatures within a rather wide range. The values are approximately 0.5 minutes at 1292° F., 0.2 minutes at 1382° F., 0.012 minutes at 1562° F., and somewhat less than 0.003 minutes at 1742° F.

These values may be used to determine a

time-temperature relation which is expressed in a compact form by the equation

$$T = 1245 - 180 \log_{10} t,$$

in which "T" is temperature in degrees Fahrenheit, and "t" is time in minutes. The time given by the formula is a minimum value for the formation of a substantially maximum yield of benzol.

In practice, a reaction time as much as several fold greater may be used without loss in benzol yield. Since the literature shows that the time consumed by the initial decomposition of gaseous paraffins to form gaseous olefines is only a small fraction of the total time found to be required for forming a yield of benzol, it is obvious that the same time-temperature relation is applicable to the treatment of gaseous olefines to form benzol and to all the simpler paraffins which decompose into gaseous paraffins and gaseous olefines. Methane, because of its great stability to heat is not converted into benzol under the above mentioned time-temperature conditions.

This formula gives the minimum time of cracking to develop a substantially optimum yield of light oil at any temperature within the range. Since the oil yield in the early stages of exothermic cracking increases rapidly with prolonging of exposure, the formula may, perhaps, give an oil yield as much as 25 percent less than optimum, but it does define the more sensitive lower exposure time limit. An exposure of from 2 to 6 times this length will actually give an optimum light oil yield, and exposure times in the range 2 to 6 times the formula value would actually be used, the selection depending on gas depletion, tar yield permissible, etc., within the range 1250-1550° F. From 1550 to 1750° F. the high rate of self-heating and complications due to heat transfer, rendered our work less accurate, but we have actually obtained optimum yields at exposure times twice that calculated by the formula at temperatures up to 1922° F.; well above the range.

A several fold increase in the period of cracking above the shortest period above specified, which will give a virtually optimum yield of volatile oil causes relatively little change in yield. The oil produced at 1562° F. by the cracking period of .02 minutes given by the formula contains 20% or so of unsaturates, chiefly butadiene and cyclopentadiene. The remainder is benzene, toluene and xylene. The oil produced by a longer cracking period, say .10 minutes contains over 90% benzene, and less than 3% unsaturated hydrocarbons; the optimum yield of volatile oil is substantially constant over the temperature range of 1250° F. to 1750° F.

We propose to take advantage of the exothermic stage of the cracking operation and to control said stage so as to crack hydrocar-

bon gases to form oils in a reaction chamber in which conversion occurs at a temperature advantageously higher than that of the gas, and this without the addition of extraneous heat during the exothermic stage, this being possible by reason of a predominance of exothermic reaction. Broadly stated, our discoveries indicate that the oil forming stage in the cracking operation takes place exothermically within the approximate range

of 950° F. to 1750° F., the range preferably being between 1100° F. and 1750° F. The composition of the gas to be exothermically cracked or converted, may vary greatly. We have ascertained that paraffins higher than methane will absorb heat in cracking. Gaseous olefines, especially ethylene, have a positive heat of formation. In cracking to form oils of higher carbon content, methane, which has a high negative heat of formation, is formed in a relatively large amount, whether hydrogen is, or is not present. These facts account for most of the exothermic effect. The maximum exothermic effect will be obtained with a gas containing a maximum concentration of gaseous olefines and a minimum concentration of paraffins higher than methane. The calculated temperature rise during the exothermic stage of the cracking of butane, for example, at approximately 1562° F., to give a maximum yield of simple aromatics, is approximately 350° F. A temperature rise, from this cause, of over 200° F. has been obtained in large scale operations, which will be specifically set forth hereafter. If a rise in temperature of 50° F. be considered the minimum which will give a practical advantage, the weight percent of gaseous olefines need not greatly exceed that of the paraffins higher than methane.

In this connection it may be well at this time to direct attention to the accompanying drawings, in which Figs. 1, 2, 3 and 4 are diagrammatic views, partly in vertical section, of suitable apparatus for use in practicing our improved processes.

Referring to Fig. 1, we have passed, for example, 8924 cubic feet per hour of a gas consisting chiefly of butane through a coil of three and one-half inch tube, 200 feet long, into which heat was introduced by convection of combustion gases in the cooler parts, and radiation in the hotter. As the rate of firing was increased, the temperature of the gas leaving the tube coil increased rapidly, until it reached 1300° F. After reaching this point, the temperature rose very slowly to 1400° F. while the rate of firing was greatly increased. The linear temperature gradient in the tube coil was from 1300° at the beginning to 1400° F. at the end of the last section of the coil, in which section the heat increment was known to be many times large enough to heat the gas 100° F. Both

- these effects show heat absorption to be due to endothermic reactions. The rate of reaction and hence of heat absorption, increases with increase in temperature. Obviously, with a rate of heat introduction of about 200 B. t. u. per minute per linear foot of tube in an 80 foot section in which most of the cracking is taking place, and with 20 pounds of gas passing per minute, the temperature of the 10 gas will rise only to such a value that the rate of reaction and hence, the rate of heat absorption is such that 20 pounds will absorb $80 \times 200 = 16,000$ B. t. u. in the time of contact of the gas, which was about 0.005 minutes 15 in the section of the tube coil where cracking took place. The temperature would show almost no gradient from point to point of the cracking section if the reaction rate did not decrease as the original constituents were 20 destroyed, but since it does, a small temperature gradient is to be expected, the equilibrium temperature attained being somewhat higher near the end of the endothermic stage of cracking than at the beginning.
- 25 When enough heat was introduced to raise the temperature of the gas leaving the tube to above 1450° F., the temperature fluctuated, as would be expected from the onset of the exothermic cracking, which would magnify 30 fluctuations in gas rate or heat input. In our example, gas issuing at 1435° F. from the tube coil with a specific gravity of 0.94 (air=1.00) and over 40 percent unsaturates was passed through an insulated cracking 35 chamber 6, of .273 cubic feet capacity, in which the temperature rose to 1520° F. and the gas left the chamber at 7 with a specific gravity of 0.55 and a high content of benzol. This corresponds to a 0.20 minute duration 40 of exothermic cracking at a mean effective temperature of 1500° F. which is six times as long as the minimum time of 0.037 minutes for developing an optimum light oil yield. A much longer exposure than 0.20 minutes 45 would result in destruction of light oil, but we have found an exposure at this temperature six fold greater than the minimum given by the formula, while causing depletion of the cracked gas in heating value, produces a 50 maximum yield of light oil more free from gum forming unsaturates than with the minimum exposure time.
- The converted gaseous mixture leaving the reaction chamber 6, may be passed by suitable conduits 8 and 9, first through a scrubber 10, and afterwards through an extraction plant 11; the light oils being separated from the gas in the latter, and being partially suitable for motor fuel purposes.
- 55 As indicated, our process of exothermically cracking hydrocarbons may be applied to other hydrocarbons than the gaseous paraffins. For example, the gases formed in the pressure distillation of petroleum, contain paraffins higher than methane, as well as gaseous

olefines, and this product is suitable as the initial starting material. A certain amount of endothermic cracking, somewhat less than that required for ethane, propane, and butane, is necessary before such gases are in a suitable condition to undergo exothermic cracking.

As an example of pressure still gases suitable for treatment by our process, the following is typical:

CO ₂ and H ₂ S	1.
Olefines	9.
Hydrogen	5.
Paraffins }	85. 80
Nitrogen }	100.

Calorific value 1800 B. t. u. per cubic foot.

The calorific value indicates 50 percent by weight or so of paraffins higher than methane. The olefines are largely propylene and butylene. This gas would require some endothermic cracking at about 1400° to initiate exothermic cracking. A propane-butane concentrate of cracking still gases would be even more suitable for cracking to benzol. Such a material containing 5 percent propylene, 25 percent propane, 35 percent butylenes, 35 percent butane has been obtained by us from pressure still gases.

The initial starting material may furthermore be the gases formed in vapor phase cracking, and these are particularly suitable since they contain as high, in some cases, as 75% olefines. Such gases will crack exothermically after only such a pre-heating as is necessary to initiate a moderate rate of exothermic reaction.

As an example of a gas produced by vapor phase cracking, it may contain 50 percent unsaturates, with a calorific value of 1800 B. t. u. With the cracking conditions used, such a gas would contain less ethane than unsaturates, and would need little if any endothermic cracking to initiate exothermic cracking.

Petroleum may be cracked at temperatures of 1200 to 1600° F. almost wholly to produce gases containing a large proportion of gaseous olefines, and such gases will undergo, according to the present invention, exothermic cracking.

From the above, it is seen that gases typified by ethane, propane and butane, and mixtures of these gases, are fairly rapidly endothermically cracked at temperatures somewhat above 1250° F. with a considerable absorption of heat and with the formation of negligible amounts of oils, tar and carbon. The further cracking of the products of such endothermic decomposition or conversion proceeds exothermically, and at a somewhat considerably slower rate to form aromatic coils, tar and, in some cases, finally carbon.

It is to be noted that an increase in temperature in both stages of the cracking operation, that is, the endothermic stage and the exothermic stage, decreases the time consumed in each stage to crack and obtain the desired results.

Broadly, in accordance with our invention, we propose to conduct the cracking operation in two stages, an endothermic stage, and an exothermic stage, and this, under peculiarly suitable circumstances for each stage; and in general, the heat required for the endothermic stage, may be introduced through any confining surface. For example, the gas may be passed through the coil tube 5, through which heat is applied externally. The temperature obtained in different parts of the tube are, generally speaking, the result of a balance between the rate of endothermic reaction and the rate of heat introduction. Our experiments indicate that a temperature range of 1150° to 1500° embraces the more practical values. Owing to the high velocity of the reactions occurring, cracking may be conducted economically in large scale operations at a temperature between 1300° F. and 1450° F. with the gas at a pressure of only a little above atmospheric.

The temperature balance has been explained above. It may be mentioned that it can be put more clearly in mathematical form, but this would not be especially useful, since the several controlling factors cannot all be evaluated, as, for example, the change of velocity of endothermic heat absorption with extent of endothermic cracking, but the practical temperature range of 1300° F. to 1450° F. or 1500° F. for conducting the endothermic cracking near atmospheric pressure is practicable for an iron or alloy tube coil in which the maximum practical coefficient of heat transfer is used.

The exothermic stage may be conducted in the chamber 6, through the walls of which no heat is introduced, and in which the carbon which forms during the operation may deposit.

Regarding the insulated chamber, we have used a cylindrical chamber of 273 cubic feet capacity of a length of about four times the diameter. The insulation was supplied by building the wall 18 inches thick of firebrick and Silocel insulation brick. The lining is of firebrick. It is encased in a steel shell and stands on one end. The gas, after endothermic cracking was introduced at the bottom at a temperature near that at which it left the tube coil and was discharged from the top after exothermic cracking had taken place during its passage. The direction of flow from bottom to top is preferred to the reverse direction, because the small decrease in specific gravity during exothermic cracking would, in the latter arrangement, tend to cause circulating and consequently, discharge

part of the gas undercracked and part overcracked.

Our experiments indicate further that the maximum yield of aromatic compounds is approximately constant over a relatively wide range of cracking temperature. Therefore, owing to the comparatively long time required to effect the desired results in the exothermic cracking stage, it is permissible and desirable to conduct it at a higher temperature than is obtained in the endothermic cracking stage, and thereby reduce the size of the reaction chamber needed. By providing the reaction chamber with adequate insulation, heat developed by the reaction may be used to attain this higher temperature without mixing additional heating gases which would lower the quality of the gases produced by the process, and this is particularly desirable if the initial starting materials are such and the process is carried out so as to produce a fuel gas. In extreme cases, however it may be necessary to impart a helpful temperature increment prior to the exothermic cracking stage. However, if this is necessary, and if heated gases are used for this purpose, only a small amount thereof is necessary to impart a helpful temperature increment, since little of the added heat is absorbed by endothermic reaction.

Regarding the addition of heat prior to exothermic cracking in the chamber 6a (see Fig. 2), the following is an example: If the raw gas were simply heated to 1300° F. about 1300 B. t. u. per pound would be required. If products of combustion at nearly flame temperature were added by way of pipe 12, to complete endothermic cracking, enough would need to be added to impart 700 B. t. u. per pound of heat of reaction, whereupon exothermic reaction would set in and a gas be produced containing benzol and perhaps 35 per cent inerts. This not only would reduce the quality of the gas, but, since the presence of tar and carbon suspension would rule out good heat recovery in some cases, the sensible heat carried by the inerts would need to be lost. If, however, the raw gas were heated to 1300° F. and then all the endothermic heat introduced in a tube coil within the range 1300-1400° F. no such heating gas would need to be added and yet, the tube coil would be exposed to a temperature only 100° F. higher. If a checkered passage were alternately heated and used for endothermic cracking, or if the gas were cracked under superatmospheric pressure at a lower temperature by reason of a longer time of residence in the tube coil, or if the endothermically cracked gas were conducted through an interconnecting tube and cracking chamber, in which a loss of 100-400° F. of sensible heat was permitted, the gas supplied to the cracking chamber 6 or 6a would be endothermically cracked, but too cool sometimes to under-

go prompt exothermic cracking. In such cases, it would be useful to introduce by way of pipe 12, say, just the small amount of heated products of combustion, (say about 5 15% by volume) needed to impart enough sensible heat to initiate a fair rate of exothermic cracking. The gas produced would contain only a little inerts.

In the case of gases such as those from 10 vapor phase cracking, which would absorb a negligible amount of endothermic heat, the gas could be preheated to 1100° F. in the tube coil 5a, at which temperature the life of the tube would be longer and the cost lower, 15 than at higher temperatures. The gas could then be heated to 1400° F. by introducing hot products of combustion through pipe 12 (rapid mixing should reduce heat absorption from the water gas reactions forming carbon monoxide), and the gas could then undergo self-heating and exothermic cracking to benzol.

We will now proceed to described the process broadly, and, thereafter, several variations thereof.

Gases containing a substantial amount, preferably over 15% of hydrocarbons higher than methane, that is, hydrocarbons such as ethane, propane, and butane, are subjected, 30 preferably in the tube coil 5 or 5a, to sufficient preheating accompanied by endothermic cracking to initiate the exothermic stage of cracking to produce the olefines, which is then allowed to proceed in the chamber 6, under 35 the conditions previously described, until a maximum yield of aromatic compounds and oils has developed. For example, butane may be passed through the tube coil in which it is cracked, preferably within a temperature 40 range of 1300° to 1400° F., and discharged at 1450° F. with a specific gravity of 1.08 (air=1.00), and an unsaturated content of over 40% by volume. This gaseous product may then be passed through insulated reaction 45 chamber at the exit of which temperature ranges of preferably 1450° to 1650° F. are developed. At temperatures within this range, the optimum yield of aromatic compounds, or oils, is obtained.

50 However, if it is desired, the process, by a slight variation, will produce carbon and hydrogen as the substantial end products. This will occur if the exothermic reaction is allowed to proceed far enough to a temperature 55 above 1600° F., and that temperature is maintained long enough to accomplish the desired decomposition. The hydrogen containing gas produced in accordance with the above will contain methane. However, this 60 may be reduced by using in the exothermic reaction chamber a suitable catalyst, such as carbon. Equivalent means may be used to increase the hydrogen content, and thereby make the hydrogen suitable for hydrogenation. 65

If hydrogen for hydrogenation is desired, the chamber 6 or 6a may be filled with coke to act as a catalyst for increasing the hydrogen content, but such means cannot be used to increase it greatly. The gas is, however, 70 suitable for conversion into a purer hydrogen by other means, such as decomposition with steam.

The exothermic cracking chambers may be subjected to fluctuations in temperature, and it is desirable to provide means for reducing the temperature of fluctuations and inequalities during the cracking operation. This may be accomplished by disposing fire-brick or other suitable heat absorbing material in 80 the exothermic cracking chamber.

The use of a checker brick filling for the reaction chamber, as indicated at 14 in Fig. 3, would not remove fluctuations in temperature of long period, due to changes in self-heating as flow rate or temperature of incoming gases varied, but the brick will smooth out fluctuations of short period by absorbing heat when the temperature of the gases rises above the brick temperature, and give it off when the gas falls below. Fluctuations of longer period or temperature drift however might need to be controlled by introduction of cold diluent gases through the pipe 12 in Fig. 2. The checker brick might be of further advantage in smoothing out inequalities of cracking in this, that the small pressure gradient it would cause might assist in giving all portions of gas an equal time of passage 95 through the chamber, as by reducing eddy currents out of the main path of the gas. A vertical cylindrical cracking chamber filled with cracker brick could be used. It might, for example, have about the same cubic content of empty space as if not brickwork were 100 used, but brick would take up about 40% of space, making the chamber somewhat larger.

Fluctuations in the rate of flow, the temperatures and composition of the gases entering the chamber to undergo exothermic cracking, are magnified in the temperature attained in the exit end of the chamber 6, 6a or 6b, because of the high rate of self-heating 110 at the high temperature developed. Since small variations in extent of cracking greatly effect the characteristics of the final product, the extent of cracking must be confined within narrow limits. When the rate of flow of the gas undergoing cracking and heat input preceding introduction to the cracking chamber is varied, as a means of maintaining a constant extent of cracking owing to the inertia of the system, due chiefly to storage of heat, considerable fluctuation in cracking results, and excessive cracking occurs periodically.

115 A closer control may be obtained by the introduction of a cooling diluent in a small amount through the pipe 12, as heretofore 120

mentioned, either in the gas before it enters the exothermic reaction chamber, or at some point within the chamber other than the exit. For this purpose, gas to be cracked, gas resulting from cracking, fuel gas, and the like, may be used. The rate of introduction may be controlled continuously by a characteristic of the cracked gas, say temperature, measured on the gas just before leaving the cracking chamber. In this connection, see Fig. 2.

The temperature attained within the top of the chamber 6 will be the temperature at which gas is introduced at the bottom, plus that temperature rise due to self-heating by exothermic reaction, minus the temperature drop due to heat loss through the chamber walls. The temperature rise, due to self-heating, depends on the composition of the gas entering the chamber, the temperature at which it enters, and the temperature-time relation as it passes through the chamber.

For a given constant composition, temperature, and velocity of gas entering the reaction chamber, there would be a constant extent of cracking maximum temperature attained if no heat were thrown back by the self-heated gas to gas which had as yet undergone less self-heating, but since there is, the heat thrown back can increase the rate of self-heating gradually even under these constant conditions of the entering gas. The resulting temperature climb would eventually result in overcracking. The rate of firing the tube, coil 5a, in which the endothermic cracking took place could be suddenly decreased to arrest the temperature rise. But if this were done, the temperature climb in the top of the cracking chamber could still go on while the furnace reached the new lower temperature equilibrium, and when the temperature rise did stop, if the rate of heating had been reduced a little too much, in order to bring about a quick response, the chamber temperature would drop, less heat would be thrown back, less self-heating then take place, and the chamber temperature would continue to drop. Heat loss through the chamber walls could reduce this fluctuation somewhat, but this would necessitate more heat introduction in the tube coil, which it is desirable to keep at a minimum. The effect of magnifying in outlet temperature small fluctuations in inlet temperature is then to be expected.

The introduction of cold diluent gas through pipe 12 to arrest temperature climb, does so, both by reducing the inlet gas temperature, and hence rate of initial self-heating, and by decreasing the time of passage, and hence time of self-heating. Both these effects take place at once on introduction of cold gas. The heat introduced in the tube coil 5a would need always to be so great that no fluctuation in operating conditions would

permit the exothermic cracking temperature to drop off, so a slight average excess of heat would need to be introduced. The amount of diluent gas would need to be great enough to prevent excessive temperature rise, when the fluctuation in operating conditions causes maximum values. With ideally constant conditions in the tube furnace, the correct degree of exothermic heating would take place, and the amount of diluent gas would be vanishingly small. Presumably, with the firing of the tube furnace and the flow rate of raw gas under good control, the amount of diluent would never need to exceed 5% of the gas being cracked, and the amount would vary between 5% and zero as fluctuations were offset when they appeared.

The temperature attained, the unsaturates content and specific gravity of the completely cracked gas, are all properties which vary greatly enough with extent of cracking to permit their continuous determination to be used as an index of extent of cracking and means of controlling the introduction of diluent gas. Temperature is a convenient index to use, and it could be used either to regulate the rate of continuous introduction of diluent gas or percentage of time open of an open-and-shut valve device. For example, the introduction of the cold diluent gas may be advantageously controlled by use of a thermocouple 15 (Fig. 2) or the like, which utilizes conditions at the top of the cracking chamber 6a to control the operation of valve means 16 which regulates the admission of the cold gas.

Our experiments also indicate that the formation of carbon proceeds rapidly in the exothermic cracking stage, if the cracking continues after the maximum yield of benzol has developed. The high rate of cracking at the conclusion of the exothermic stage aggravates the trouble due to carbon formation. The extent of cracking may be better controlled, and carbon decomposition in the exit pipe 17 (Fig. 3), reduced by introducing at the point of exit from the chamber, enough cold gas to reduce the temperature to such a degree that further cracking is virtually arrested. The introduction of cold gas to arrest cracking would have to be done between the exit 17 and the thermocouple 18 measuring the maximum temperature developed and used to control extent of cracking. The amount to be introduced through pipes 19, for instance, to reduce the temperature from a reasonable value of 1550° F. to 1400° F., at which latter temperature cracking would be nearly arrested, would be about 10% by weight of the gas cracked. The introduction will be continuous and at a fixed rate.

Since the velocity of the exothermic reaction is greatly increased by a rise of temperature, the accelerating of the temperature rise, especially in the early stage of the exo-

thermic cracking, will permit a smaller size for the reaction chamber for a given amount of gas to be put therethrough. This may be accomplished by introducing the endothermically treated gas so as to provide turbulence, thereby mixing the incoming gas with the gas which has already undergone some self-heating. In the last stages of cracking, however, turbulence is undesirable, because a portion of the undesirable liquid unsaturates, and olefine gases will be discharged before their conversion occurs. In the latter stage, moreover, temperature instability becomes serious, and the state of cracking must be controlled. This control may be accomplished by providing an exothermic cracking chamber 6c which consists of two adjoining chambers 6d and 6e, communicating by one or more constricted openings 6f. The gas enters the lower chamber through a pipe 20, directed in such a manner that active turbulence is induced in the chamber 6d to cause mixture of the incoming gas with gas that has already undergone some exothermic cracking. The gas then passes through the restricted opening (where cold gas is introduced through a pipe 21 at an adjusted rate to maintain a constant extent of cracking), into the adjoining chamber 6e, through which it moves in an upward direction to an exit 22, at which cold gas may be introduced, if desired, (as at 19 in Fig. 3), to arrest the cracking.

Our experiments, in which hydrocarbons are cracked first endothermally, and then exothermally, while controlling the relationship between the temperature employed in and the duration of each cracking stage to produce an optimum yield of aromatic compounds, have been carried out under atmospheric pressure or slightly above, but it is clear that the process may be carried out at higher pressures.

The terms and expressions employed hereinafter are used as terms of description and not of limitation, and there is no intention in the use of such terms and expressions, of excluding any equivalents of the features shown and described, or portions thereof, but it is recognized that various modifications are possible within the scope of the invention claimed.

What we claim and desire to secure by Letters Patent is:

1. The process of converting hydrocarbons, comprising thermally treating raw hydrocarbon fluids to produce a gaseous mixture of aliphatic hydrocarbons containing an olefine content sufficient to insure subsequent exothermic cracking and having a temperature between 950° F. and 1500° F. suitable for exothermic conversion, then subjecting said mixture without the addition of heat to exothermic cracking at a temperature between 1250 and 1750° F. for an interval of

time substantially as expressed by the formula $T = 1245 - 180 \log_{10} t$, to convert the olefines into heavier hydrocarbon oils, and then separating said oils so produced.

2. The process of converting hydrocarbons, comprising thermally treating raw hydrocarbon fluids to produce a gaseous mixture of aliphatic hydrocarbons containing an olefine content sufficient to insure subsequent exothermic conversion and having a temperature between 950° F. and 1500° F. suitable for exothermic conversion, then subjecting said mixture without the addition of heat to exothermic cracking at a temperature between 1250 and 1750° F. for an interval of time substantially as expressed by the formula $T = 1245 - 180 \log_{10} t$, to convert the olefines into heavier hydrocarbon oils, introducing a cold diluent gas into the mixture during the exothermic reaction for controlling such reaction, and then separating said oils so produced.

3. The process of converting hydrocarbons, comprising thermally treating raw hydrocarbon fluids to produce a gaseous mixture of aliphatic hydrocarbons containing an olefine content sufficient to insure subsequent exothermic conversion and having a temperature between 950° F. and 1500° F. suitable for exothermic conversion, mixing a hot diluent gas with said mixture to obtain said temperature, then subjecting the combined mixture without the addition of heat to exothermic cracking at a temperature between 1250 and 1750° F., for an interval of time substantially as expressed by the formula $T = 1245 - 180 \log_{10} t$, to convert the olefines into heavier hydrocarbon oil, and then separating said oils so produced.

4. The process of converting hydrocarbons, comprising thermally treating raw hydrocarbon fluids to produce a gaseous mixture of aliphatic hydrocarbons containing an olefine content sufficient to insure subsequent exothermic cracking and having a temperature between 950° F. and 1500° F. suitable for exothermic conversion, then passing said mixture without the addition of heat through an exothermic cracking zone at a temperature between 1250 and 1750° F. for an interval of time substantially as expressed by the formula $T = 1245 - 180 \log_{10} t$, to convert the olefines into heavier hydrocarbon oils, introducing into the exit end of said zone a cold diluent gas for controlling said final temperature, and then separating said oils so produced.
